UNITED STATES PATENT OFFICE.

VINTON E. SISSON, OF CHICAGO, ILLINOIS, ASSIGNOR TO UNION METAL PRODUCTS COMPANY, OF CHICAGO, ILLINOIS, A CORPORATION OF DELAWARE.

SHEET-METAL END FOR RAILWAY CARS.

Application filed July 18, 1924, Serial No. 726,816, and in Canada May 19, 1924.

This invention relates to improvements in end structures for railway cars and more particularly to sheet metal ends for freight cars. 5
The end of a freight car is subject to very severe shocks and stresses on account of the tendency of the cargo to shift when the train starts or stops, and in switching, and also to the tendency of the superstructure 10 of the car to weave while the train is in motion. To strengthen this type of car, ends have been constructed of one or more sheets or panels of metal, usually steel, which sheets or panels are formed with corrugations for 15 rigidifying the structure to more readily meet impacts from without, cargo thrusts from within, and the racking strains from weaving.

It is the object of this invention to provide 20 an end of the sheet metal type which is adaptable to either wooden car frames or all metal freight cars and that may be employed for strengthening gondola cars, box cars, or other similar cars. It is a further object of 25 this invention to provide the sheets or panels of the end with corrugations of particular form and length that are peculiarly adapted to strengthen the end to meet the stresses and strains already described. While the 30 corrugations are preferably formed parallel, their relation to each other or their direction is immaterial, likewise the corrugations may be all pressed from one side of the sheet of metal or may be formed from opposite sides, 35 as desired.

While the preferred forms of this invention are illustrated upon the accompanying sheet of drawings, yet it is to be understood that minor detail changes may be made without departing from the scope thereof.

In the drawings:

Fig. 1 is an end elevation of a box car illustrating an embodiment of my invention.

Fig. 2 is a section along line 2—2 of Fig. 1.

45 Fig. 3 is a view similar to Fig. 2 illustrating the attachment of the end to an angle iron frame member of a car.

Fig. 4 is similar to Fig. 3 and shows the 50 relation of the attaching means and the termination of the two sets of corrugations.

Fig. 5 is a fragmentary elevation of Fig. 4.

Fig. 6 is a half end elevation of a box car illustrating an embodiment of my invention wherein the end sheets are secured together

along a vertical line and provided with vertical corrugations. 55

Fig. 7 is a section along line 7—7 of Fig. 6. Sheet metal ends comprising corrugated panels have been employed on freight cars of different types, in some of which the corrugations merge into the plane of the panel leaving a flat marginal portion about the edges, while in others the corrugations are extended through to the end of the panel. There are certain objectionable features to 65 both of these forms.

In the first instance, the corrugations are usually terminated short of the corner post to allow the flat marginal portion to rest thereon and provide a space for bolts or 70 rivets to be passed through the panel and post to secure the panel in position, with the result that the main body of the panel is strengthened by the corrugation, yet there is a considerable portion on each end; 75 namely, the flat margin, which possesses only the normal strength of the sheet of metal from which the panel is formed. In the other instance, in which the corrugations are extended through to the ends of the panel an additional closure and securing member is necessary to attach the panel properly to the frame of the car and to form a watertight closure. 80

Fig. 1 illustrates an embodiment of this 85 invention as applied to the end of a box car showing the manner in which the above objectionable features are overcome. The panel is provided with a plurality of horizontal contiguous corrugations which merge 90 at their ends into the plane of the panel. In accordance with this improved structure alternating corrugations are terminated and merged into the plane of the panel short of the corner post, while the other alternating 95 corrugations are continued therebeyond and merge into the plane of the panel adjacent its ends, thereby providing flat surfaces in the plane of the panel between the latter corrugations which rest upon the corner 100 posts. The corrugations which terminate short of the corner post are not necessarily positioned alternately with those which are continued beyond the corner post.

The attaching bolts 5 or rivets 8 are positioned in the flat surface between the terminations 15 of the corrugations 4, which overlap the frame member. This relation 105

of the termination 15 of the corrugation and the attachment makes the corrugation a restrained beam which greatly increases its strength against deflection. Additional means for attaching the panel to the frame member may be provided by the use of bolts 6, which are adjacent the ends of the corrugations 4, which overlap the frame member, and it will be noted that these bolts 6 are aligned with these corrugations. For this construction see Figs. 1 and 2. These additional means may be in the original plane of the panel, as shown by rivets 14 in Figs. 4 and 5 and bolts 13 in Fig. 6.

14 The application of this end to a car having a wooden frame is shown in Figs. 1 and 2, and as is customary in this type of car, the panel 1 is flanged at its ends to embrace the corner posts 3. The corrugations are shown 20 as being formed from opposite sides of the metal sheet and therefore extend alternately on opposite sides of the plane of the panel. The inner corrugations 2 are terminated and merge into the plane of the panel short of 25 the corner post 3 so that the flat margin of the panel in line with these corrugations may be secured by bolts 5 passing through the corner post and end surface of the panel. The panel is also secured by bolts 6 passing 30 through the corner post and end flange of the panel engaging the outer side of the post. The oppositely disposed alternating corrugations 4 are continued beyond the inner corrugations 2 and, while shown as 35 terminating and merging into the plane of the panel adjacent the flanged end, the corrugations may be extended into said flange without departing from the scope of this invention.

40 This improved end attached to a car having a metal frame is illustrated in Figs. 3, 4 and 5 in which the corner post comprises an angle iron 7 with the end of the panel secured on the inner side of one arm of the 45 angle iron by rivets 8. It is obvious in this form that the relation of the alternating short and long corrugations must be reversed from that shown in the other figures. The corrugations 4 terminating adjacent to the 50 edge of the panel are arranged on the inner side of the end with the alternating corrugations 2 terminating short of the corner post on the outer surface of the panel providing a flat surface in line with the shorter corrugations and in the plane of the panel for the 55 attaching rivets 8.

Figs. 4 and 5 show a construction where the corrugated panel is secured to the corner post 7 by means (8) positioned between the 60 corrugations 15 and also by additional means (14) which are positioned in alignment with the corrugations.

The corrugations may be formed with their main portions all the same length and 65 with their terminal portions of different

length, i. e., some terminal portions longer than others. (See Fig. 1.) Preferably the alternating corrugations have longer terminal portions than the corrugations therebetween.

In both forms shown the entire surface of the panel from end to end is reinforced and strengthened by the corrugations and the car end, as a whole, possesses greater strength than the strength of the sheet of metal from 70 which it is formed and makes a watertight closure for the end of the car without any additional means or substantial change in the mode of attaching reinforced ends of 75 this general type to the car frame.

When the corrugations are positioned vertically, as shown in Figs. 6 and 7, some of them terminate and merge into the plane of the panel short of the end plate 10 or end sill 11 or both, while other corrugations continue therebeyond and overlap these frame members and merge into the plane of the panel adjacent its edge or edges.

By positioning the truss rods 12 or other attaching means on the flat surface between 90 the termination of the corrugations which overlap the end sill or end plate, and furthermore, by positioning additional attaching means 13 adjacent the ends of the corrugations which terminate into the sheet 95 short of the end sill or end plate; the same advantages are obtained as described in connection with means for attaching the end to a corner post.

This is a continuation in part of my application Serial No. 414,059, filed October 1, 1920.

I claim:

1. A metal panel for car ends having a corrugation formed therein with its opposite ends merging into the panel adjacent the panel ends, and another corrugation formed therein with its opposite ends merging into the panel at a distance from the panel ends.

2. A metal panel for car ends having a plurality of corrugations formed therein with their opposite ends merging into the panel adjacent the panel ends, and a plurality of other corrugations formed therein with their opposite ends merging into the panel at a distance from the panel ends.

3. A metal panel for car ends having alternating corrugations formed therein with their opposite ends merging into the panel adjacent the panel ends, and other alternating corrugations formed therein with their opposite ends merging into the panel at a distance from the panel ends.

4. In a railway car having corner posts, a metal end therefor including a panel having a plurality of long corrugations and a plurality of short corrugations formed therein, said short corrugations terminating short of the corner posts and said long corrugations terminating adjacent the panel ends.

5. In a railway car having corner posts, a metal end therefor including a panel having a plurality of long corrugations and a plurality of short corrugations formed there-in, said short corrugations merging into the panel and forming flat marginal portions between their termination and panel ends, said long corrugations merging into the panel adjacent the panel ends, and means 10 attaching said flat marginal portions to said corner posts.
6. In a railway car having a frame member, a metallic end therefor including a panel formed with a plurality of corruga-tions, some of said corrugations extending substantially to the frame member, and some of said corrugations overlapping the frame member, means to secure said panel to said frame member positioned between the ends 15 of the last mentioned corrugations, and additional means to secure said panel to said frame member positioned in alignment with the first mentioned corrugations.
7. In a railway car having frame mem-bers, a metallic end therefor including a panel formed with a plurality of corruga-tions of different length, the shorter corrugations extending substantially to said frame members, and the longer corrugations 20 overlapping said frame members.
8. In a railway car having frame mem-bers, a metallic end therefor including a panel formed with a plurality of corruga-tions of different length pressed from the 25 opposite sides of the plane of the panel, the shorter corrugations extending substantially to said frame members, and the longer corrugations overlapping said frame members.
9. In a railway car having frame members, a metallic end therefor including a panel formed with a plurality of corrugations, some of said corrugations extending sub-stantially to the frame members, and some 30 of said corrugations overlapping the frame members, and means to secure said panel to said frame members positioned between the ends of the last mentioned corrugations.
10. In a railway car having a frame mem-ber, a metallic end therefor including a panel 35 formed with a flange and a plurality of corrugations terminating within the edge of the panel, some of said corrugations extend-ing substantially to the frame member, and some of said corrugations overlapping the 40 frame member, means to secure said panel to said frame member positioned between the terminations of the last mentioned corruga-tions, and additional means to secure said
- flange to said frame member positioned in alignment with the first mentioned corrugations.
11. In a railway box car having a frame member, a metallic end therefor including a panel formed with a plurality of corruga-tions terminating within the edge of the 45 panel and overlapping the frame member, means to secure said panel to said frame member positioned between said corruga-tions, and additional means to secure said panel to said frame member positioned in alignment with said corrugations.
12. In a railway box car having a frame member, a metallic end therefor including a panel formed with a flange and a plurality 50 of corrugations terminating within the edge of the panel and overlapping the frame mem-ber, means to secure said panel to said frame member positioned between said corruga-tions, and additional means to secure said flange to said frame member positioned in alignment with said corrugations.
13. In a railway car having a frame mem-ber, a metallic end therefor including a panel 55 formed with a plurality of corrugations over-lapping the frame member, means to secure said panel to said frame member positioned between the ends of the corrugations, and additional means to secure said panel to said frame member positioned in alignment with the corrugations.
14. In a railway car having a frame mem-ber, a metallic end therefor including a panel 60 formed with a flange and a plurality of corrugations terminating within the edge of the panel, said corrugations overlapping the frame member, means to secure said panel to said frame member positioned between the terminations of the corrugations, and additional means to secure said flange to said frame member positioned in alignment with the corrugations.
15. A metal panel having a plurality of corrugations formed therein, each corruga-tion comprising a main portion and terminal 65 portions, the main portions being all the same length but some of said terminal por-tions being longer than other said terminal portions.
16. A metal panel having a plurality of corrugations formed therein, each corruga-tion comprising a main portion and terminal 70 portions, the main portions being all the same length and the terminal portions of the alternating corrugations being longer than the other corrugations.

VINTON E. SISSON.
